WATER COOLER FOR ELECTRIC
REFRIGERATORS

Harry J. Clark, Philadelphia, Pa.

Application March 14, 1941, Serial No. 383,400

3 Claims. (Cl. 62—89)

This invention relates to water coolers for electric refrigerators and has for an object to provide for efficient cooling of water without danger of the water freezing, by virtue of the water container being insulated from the freezing unit of the refrigerator, and to provide full visibility of the container in which the water is stored, so that the amount of water therein may be readily determined.

A further object is to provide a device of this character which will be formed of a few strong, simple and durable parts, which will be inexpensive to manufacture, and which will not easily get out of order.

With the above and other objects in view, the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming a part of this specification:

Figure 1 is a perspective view of an electric refrigerator equipped with a water cooler constructed in accordance with the invention.

Figure 2 is a front elevation of the refrigerator with the door broken away to expose the water container, cooling unit and wall insulating the container from the unit.

Figure 3 is a vertical sectional view taken on the line 3—3 of Figure 1.

Figure 4 is a vertical sectional view taken on the line 4—4 of Figure 3 showing the water container disposed at the back of the refrigerator to conserve space.

Figure 5 is a detail sectional view showing the filling cap and gasket of the water container.

Referring now to the drawing in which like characters of reference designate similar parts in the various views, 10 designates a conventional electric refrigerator having a door 12, which when open, exposes the refrigerating compartment of the refrigerator so that the stored articles on the superposed shelves 13 may be accessible. In the type of refrigerator shown, the cooling unit 14 is illustrated as being disposed above the center of the top shelf.

In carrying out the invention, the water cooler comprises a container 15, preferably formed of glass, positioned on the top shelf laterally of the cooling unit 14 and disposed near the back wall 16 of the refrigerator, as best shown in Figure 4, to conserve space. An insulating wall 17 is dis-

posed in the refrigerator between the cooling unit 14 and the container 15 to insulate the container sufficiently from the cooling unit so that while the water or other liquids stored in the container may be quickly and efficiently cooled yet it cannot be frozen.

The container is provided with an integral filling neck 18, which extends upwardly through a filling spout 19 formed integral with the top wall 20 of the refrigerator. The filling spout is provided with an interiorly threaded enlarged mouth 21 which is closed by a screw cap 22.

A faucet 23 is threadedly engaged in an opening in the side wall of the container near the bottom thereof and extends outwardly into a recess 24 formed in the side wall of the refrigerator into which a glass may be inserted underneath the faucet to draw off water from the container. By unscrewing the faucet and removing the top shelf the container may be easily removed from the refrigerator for cleaning.

As best shown in Figure 5, a gasket 25 is seated on the bottom of the enlarged mouth 21 underneath the screw cap 22 to maintain a liquid and air tight connection of the cap with the filling spout so that the contents of the container cannot become contaminated.

From the above description it is thought that the construction and operation of the invention will be fully understood without further explanation.

What is claimed is:

1. The combination with an electric refrigerator having a cooling unit, of a liquid container within the refrigerator insulated from the cooling unit, a filling tube extending from the container through the top of the refrigerator, a cap closing the filling tube, and an outlet projecting from the container through the wall of the refrigerator.

2. The combination with an electric refrigerator having a removable top shelf and a cooling unit above the shelf spaced from a side wall of the refrigerator, of a liquid container on said shelf having a filling neck at the top, a filling spout in the top wall of the refrigerator connected to said neck, a cap closing said spout, an insulating wall disposed between the cooling unit and the container above said shelf, an outlet connection projecting from the container through a side wall of the refrigerator, and a depression formed in the wall of the refrigerator and said outlet for receiving a utensil to be filled from the container.

3. The combination with an electric refrig-

erator having a removable top shelf and a cooling unit above the shelf spaced from a side wall of the refrigerator, of a liquid container on said shelf having a filling neck at the top, a filling spout in the top wall of the refrigerator connected to said neck, a cap closing said spout, an insulating wall disposed between the cooling unit and

the container above said shelf, a dispensing faucet removably connected to the container and exposed beyond a side wall of the refrigerator, removal of the shelf and unscrewing of the faucet permitting of the container being removed from the refrigerator for cleansing.

HARRY J. CLARK.
